UNITED STATES PATENT OFFICE.

TAKEO TERAGAWA, OF LOS ANGELES, CALIFORNIA.

DENTAL VIBRATORY MATRIX.

Application filed February 1, 1926. Serial No. 85,270.

The present invention relates to an improved matrix device for use in dentistry, and its objects are to simplify the porcelain technology in ceramic crown and bridge dentistry, and to expedite the processes pertaining thereto.

Another object is to avoid the danger of dismembering the porcelain tip or saddle, before it is subjected to the baking process.

Another object is to produce on the porcelain tip, a smooth sharp-angled shelf or abutment which is absolutely necessary and essential in the drawing of a perfect wax pattern in making perfect fitting gold backings.

Another object is to provide means for vibrating the matrix whereby the porcelain powder is better lubricated and much more quickly condensed, and to provide means for adjusting the vibrating elements whereby to graduate the degree of vibration.

Another object is to provide improved clamping elements for the matrix, whereby the porcelain tip or saddle is automatically held in perfect adjustment in the desired position, and the engaging and disengaging of the porcelain facings is simplified.

The primary object of the invention is to provide a vibratory matrix of the character mentioned which will embody simplicity and efficiency without liability to get out of working order, which may be made within reasonable limits as to cost of production, and which may be readily operated without skilled knowledge on the part of the initiate or instructed.

To the accomplishment of the foregoing and such other objects as may hereinafter be made to appear, the invention consists in the features of construction hereinafter particularly described and then sought to be clearly defined by the claims, reference being had to the accompanying drawings, in which:

Figure 1 is a perspective view of a vibratory dental matrix embodying the present invention. Fig. 2 is a sectional view of the device. Fig. 3 is a top plan view of the device. Fig. 4 is a perspective detail view of the vibrator spring. Fig. 5 is a side elevation of a modified form of the device arranged for double capacity. Fig. 6 is a top plan view of the form shown in Fig. 5. Fig. 7 is a plan view of a modified form of the device. Fig. 8 is a side view of the form shown in Fig. 7. Fig. 9 is an enlarged and fragmentary detail view showing the device in use.

Referring to the drawings, the plate member 11, has an aperture 12 adapted to receive a tooth form 13, and includes a depending flange 14, to which is attached the handle 15. A holding member 16 is connected by hinge elements 17, with plate member 11, and serves to support the tooth form when the same is inserted in aperture 12, the arrangement being such that the edge of holder 16 is parallel with flange 14 in operative position. Holding member 16 has a depending flange 18 and a stud 19, in which is mounted a plunger 20, adapted to engage with the annular flange 21, on plate member 11. This flange has a small hole 22 in which plunger 20 engages in operative position of the holder. A spring 23 serves to actuate plunger 20, being interposed between flange 18 and a collar 24, on the plunger. The holding member 16 has other depending flanges 25, which may be pressed by the operator for adjusting the holding member.

The handle 15 has mounted therein a toothed wheel 26. A vibratory spring 27, extends in slot 28 in the handle, and has a series of adjustment holes 29. A screw 30, in the extremity of the handle 15, serves to bind the spring 27 in an operative position, and engages with one of holes 29 for adjustment. The handle has an outer portion 31, which is slidable upon the shank portion of handle 15, and is adjustable to and from the holding parts of the device, being secured in adjusted position by a set screw 32, engaging with said shank portion. The vibratory spring 27 engages with the toothed wheel 26, and when the wheel is rotated, the spring will produce a series of vibrations in all parts of the holding elements. By suitable adjustment, the spring will engage with a more or less deeper bite in the toothed wheel and produce corresponding stronger or weaker vibrations. The wheel 26 is rotated by the thumb of the operator and the vibrations serve to settle and condense the porcelain powder the more quickly in the processes for which the matrix is intended.

A movable jaw member 33 has integral supporting rods 40, which pass through flange 14, and serves to support the tooth form when the same is mounted in aperture 12. Springs 41 serve to actuate the movable jaw member, and render the same automatically operative. The plate 42 connecting rods 40, may be pressed by the operator to move the jaw member to its release position.

The spring 27 is adjustable to produce stronger or weaker vibrations as desired, and the outer portion 31 of the handle is adjustable to make the handle longer or shorter as may be desired. It may be noted that aperture 12 has a notch 10, to receive a longer tooth or to hold the tooth in a different position.

In the modified form shown in Figs. 5 and 6, the main plate 34 is fixed to the handle and has two apertures 35. The top holding member 36, has similar apertures. The vibratory elements and holding elements are similar to the corresponding elements in the device shown in Figs. 1, 2, 3 and 4.

In the modified form shown in Figs. 7 and 8, the main plate 38, has mounted thereon a slidable holding member 39. The remaining vibratory and holding elements are similar to corresponding elements shown in Figs. 1, 2, 3 and 4.

In the use of this device, the tooth form is supported as shown in Fig. 9. The processes may be readily carried on by the operator. The actuation of the vibratory elements by the operator serves to distribute and to quickly condense the porcelain powder that may be used in the process, and to cause the lubricator therefor to more quickly permeate the powder. The tooth form is quickly clamped in position, automatically retained in clamped position, and as quickly released. Through the vibratory mechanism, the processes are considerably hastened, thereby saving much time. The device further tends to secure perfect abutment edges for porcelain facings, and for fitting gold backings. The movable jaw actuated by springs, serves as a self-retainer for the porcelain facings.

The drawings illustrate a complete embodiment of my invention according to the best mode I have so far devised for its practical application, and the elements shown and described are well adapted to serve the purposes intended. It is to be understood however, that I do not wish to be limited to the precise details of construction exhibited in the drawings, but contemplate employing any modifications thereof, that may fall within the scope of the invention and the appended claims. The holder or cover 16, when the tooth form is to be removed from the matrix, may be turned back, leaving a straight edge on the tooth, whereby the same may be readily removed.

I claim:

1. In a dental matrix of the character set forth, the combination with a main plate member having an aperture therein to receive a tooth form, of a spring-actuated movable jaw mounted in opposed relation to the main plate member, a cover pivotally mounted relative to the main plate member and to swing to an operative position in op-

posed relation to the movable jaw member, and means for holding the said cover in any adjusted position.

2. In a dental matrix of the character set forth, the combination with a main plate member having an aperture therein adapted to receive a tooth form, of a spring-actuated movable jaw mounted in opposed relation to the said main plate member, a cover pivotally mounted relative to the main plate member, and capable of assuming an operative position in opposed relation to the movable jaw member, flanges depending from the said cover, a spring-actuated plunger mounted in said depending flanges and engaging frictionally with the edge of the main plate member, and a handle for the main plate member.

3. In a dental matrix of the character set forth, the combination with a main plate member having an arcuate edge and having an aperture therein to receive a tooth form, of a movable jaw member mounted in opposed relation to the main plate member and in opposed relation to said aperture, springs tending to force the movable jaw member to its closed and operative position, a movable cover in opposed relation to the movable jaw member, and having a pivotal connection with the main plate member, means for holding the movable cover in any adjusted position, a handle for the main plate member, and vibratory elements mounted in the handle.

4. In a dental matrix of the character set forth, the combination with tooth holding means, of a handle for the tooth holding means, and vibratory elements mounted in the handle.

5. In a dental matrix of the character set forth, the combination with tooth holding means and a handle for the tooth holding means, of a toothed wheel mounted in the handle and adapted for manual manipulation, and a vibratory spring mounted in the handle and having engagement with the toothed wheel.

6. In a dental matrix of the character set forth, the combination with tooth holding means, of a handle for the tooth holding means, a toothed ratchet wheel mounted in the handle and having its periphery projecting from the side of the handle for manual manipulation, a vibratory spring mounted in the handle and having engagement with the periphery of the said ratchet wheel, and means for adjusting the spring to engage more or less deeply with the teeth of said wheel.

7. In a dental matrix of the character set forth, the combination with tooth holding means, and a handle for the holding means, of vibratory means mounted in the handle, and adjusting means for the vibratory means.

8. In a dental matrix of the character set forth, the combination with tooth holding means, of springs automatically actuating the holding means, a handle for the holding means, and manually actuated vibratory elements mounted in the handle.
9. In a dental matrix of the character set forth, a plate member having a plate portion and a flange portion depending from the plate portion, and an aperture at the junction of said portions capable of receiving a tooth form, a spring actuated movable jaw mounted in opposed relation to the depending flange portion, a swinging cover mounted on the plate portion and in opposed relation to the said movable jaw member, a handle fixed to the flange portion of the plate member, and manually actuated vibratory elements in the handle.
10. In testimony whereof I hereunto affix my signature.

In testimony whereof I hereunto affix my signature.

TAKEO TERAGAWA.
